ROYAL MARCHER, OF NEW YORK, N. Y., ASSIGNOR TO COHN & ROSENBERGER, INC.,
OF NEW YORK, N. Y., A CORPORATION OF NEW YORK.

COMBINED MIRROR AND VANITY CASE.

1,416,223.

Specification of Letters Patent. Patented May 16, 1922.

Application filed November 30, 1921. Serial No. 518,828.

To all whom it may concern:

Be it known that I, ROYAL MARCHER, a citizen of the United States, and a resident of the city, county, and State of New York, 5 have invented a certain new and useful Improvement in a Combined Mirror and Vanity Case, of which the following is a specification.

This invention relates to an improvement 10 in a combined mirror and vanity case, and has for its object to provide a device in the general form of a hand mirror so arranged with suitable compartments to receive various toilet articles such as a powder 15 puff, a lip stick or the like, utilizing heretofore waste space, all of which is done without materially enlarging the outside diameter of the article.

With this object, and other objects which 20 may hereinafter appear, in view, I have devised the particular arrangement of parts hereinafter set forth and more particularly pointed out in the claim appended hereto.

Reference is to be had to the accompanying 25 drawing, forming a part hereof, in which—

Figure 1 is a plan view of my combined vanity case and mirror;

Figure 2 is a plan view of the same, with 30 the hinged mirror shown in open position, and the handle portion being broken away to disclose its interior construction; and

Figure 3 is a sectional view on the line 35 3—3 of Figure 1, looking in the direction of the arrows.

Throughout the various views of the drawings similar reference characters designate similar parts.

In the preferred embodiment of my invention, as disclosed in the accompanying drawing, 1 indicates the handle portion, which is hollow, and which widens out to form an enlarged head 2 which is substantially shallow in cross section and provides 40 a receptacle to receive a powder puff or other toilet article. Hinged at 4 is a cover 5, on the outer face of which is provided a mirror 6. The cover is provided with a catch in the form of a spring tongue 7 having an aperture 8 adapted to receive a projection 9 formed in a recess 10 on an in-turned edge or flange 11 of the receptacle 45 portion 2.

The hollow handle 1 is provided with a tubular sleeve 12 held within it and slideable within said sleeve is a tubular container 13 adapted to receive a lip stick 14 or a cosmetic of any other elongated or cylindrical character. The container 13 is secured within the end 15 of the handle and 55 said end 15 is separable from the rest of the handle 1 and is frictionally held thereon and when so held it forms a substantial continuation thereof as will be seen in Figure 1.

It will be seen from the foregoing that 60 when the device is in its closed position as disclosed in Figure 1 it presents an appearance similar to that of an ordinary hand mirror. By raising the cover 5 access is had to a powder puff and powder which 65 may be carried with the head or receptacle portion 3 of the enlarged hollow head 2 of the device. Similarly the head may be used for the reception of any other toilet articles. The lip stick 14 may be removed for use by 70 drawing out the same from the handle.

It will be obvious that my improved device may be modified in many forms as to shape and construction without departing 75 from the spirit of my invention.

Having described my invention, what I 80 claim is:—

An article of the class described comprising an article made in substantial similarity to a hand mirror, said article having a substantially flat, hollow head adapted to form a storage chamber, a hinged face on said head forming a lid therefor and having a mirror on its outer face and adapted to be swung away from the body of the article to 85 uncover the entrance to the storage chamber, a laterally extending tubular portion on said head forming a handle therefor and adapted to act as a storage chamber, a removable end on said handle forming a continuation 90 thereof, a tubular container of less thickness than the removable end, tubular means within the handle for receiving the tubular portion on the end and means for retaining 95 the end portion of the handle on the handle. 100

Signed at the city, county and State of New York, this 26 day of Nov., 1921.

ROYAL MARCHER.
